FIG. 1

Find the Plan That Best Fits You

WHAT ARE YOUR PLAN PREFERENCES?
Cost is an important factor when choosing a health plan, but not the only one.

What's more important:
LOW COST vs BROADER PROVIDER ACCESS

I strongly prefer LOW COST
I want the plan with the lowest cost in a year of my typical medical needs.

I have no preference
NEUTRAL

I strongly prefer BROADER PROVIDER ACCESS
I want to pay more for broader access and less restrictions when using medical needs.
